UNITED STATES PATENT OFFICE.

JAMES M. DODGE, OF PHILADELPHIA, PENNSYLVANIA, ASSIGNOR, BY MESNE ASSIGNMENTS, TO THE DODGE COAL STORAGE COMPANY, OF NAUGATUCK, CONNECTICUT.

CHAIN CONVEYER FOR UNLOADING CARS.

SPECIFICATION forming part of Letters Patent No. 396,197, dated January 15, 1889.

Application filed July 23, 1888. Serial No. 280,701. (No model.)

To all whom it may concern:

Be it known that I, JAMES M. DODGE, of Philadelphia, in the county of Philadelphia and State of Pennsylvania, have invented a new and useful Improved Chain Conveyer for Unloading Cars; and I do hereby declare that the following is a full, clear, and exact description thereof, reference being had to the accompanying drawings, making part of this application.

My invention relates to an improvement in that class or species of chain-conveyer apparatuses which is usually employed for taking the coal which is discharged successively from the cars of a coal-train through a suitable spout or chute into a pit and conveying the same obliquely upward to a given point of elevation, from which the coal is destined to descend by gravity to fill or supply locomotive-engines or other receptacles. In this class or species of contrivances, as is well known, it is customary to have an endless chain conveyer with the lower end of its trough located in the pit in such manner as to have the trough feed or supply coal through a suitable spout or chute, into which the coal is dumped from dumps or cars which travel on surface railway, a portion of which is located immediately over and transversely of the pit, into which the lowermost portion of the conveyer-trough descends, and as heretofore constructed or arranged both runs of the endless conveyer-chain have been located at the lower end of the conveyer within the pit and beneath the track on which the dump or car has to stand to discharge its contents into the feed-spout of the conveyer. This usual construction involves a certain depth of pit and a certain amount of ground-room in order to get the proper degree of inclination to the ascending trough of the conveyer with a given elevation from the upper end or point of discharge, and, furthermore, involves the discharge of the coal fed to the conveyer in contact with the upper run of the flighted chain, in order to feed the trough with which the lower run of the chain co-operates. Not only is the depth of the pit and the ground-space thus rendered necessary greater than is often times desirable or convenient, but, further-

more, considerable wear and tear in the machinery and sometimes clogging of the chain and other difficulties arise from the feeding of the coal onto and through the upper run of the chain in order to fill the conveyer-trough in which the lower run operates. I propose to overcome all these difficulties and to provide for use an apparatus or contrivance for the special purpose above alluded to which shall be more economic and desirable of construction, and at the same time more desirable and efficient in its mode of operation, than contrivances heretofore employed for the same purpose.

To these main ends and objects my invention may be said to consist, essentially, in the combination, with a suitable pit and feed-spout located immediately beneath the track upon which the surface cars or dumps to supply the coal are to be run, of an ordinary trough chain conveyer having its lower run and trough located at the lowermost portion thereof in the pit and beneath the car-track, but having the upper run of its flighted chain pass round about and over both the track and the car or cars to be run thereon to supply the coal, or, in other words, having its endless chain arranged in a circuit which completely encompasses the surface railroad and coal car or dump necessary to be used thereon for the supply of coal, all as will be hereinafter more fully explained, and as will be more particularly pointed out in the claim of this specification.

To enable those skilled in the art to which my improvement relates to perfectly understand and practice the same, I will now proceed to describe my invention, referring by letters to the accompanying drawings, which form part of this specification, and in which I have shown my improved apparatus or contrivance in vertical sectional elevation at Figure 1, and at Fig. 2 in an end view or elevation looking in the direction indicated by the arrow at Fig. 1.

In both figures the same parts will be found designated by the same letters of reference.

C is a pit for the accommodation of the lowermost portion of an ordinary trough chain

conveyer, by which the trough B of said conveyer extends, as shown, from the bottom of said pit obliquely upward to any desired point or elevation at which the material is to be discharged into a suitable trough or chute, from which it may descend by gravity into any desired receptacle or receptacles. This conveyer-trough B, as well as the chute D, into which the material is discharged from the upper end of the conveyer-trough, is properly secured to and supported by a suitable frame-work, (seen at A,) which frame-work also properly supports at the different localities shown a series of shafts, upon which are mounted the series of chain-wheels or sprocket-wheels e, f, g, and h, which operate to support and over or around which runs the endless conveyer-chain I, which is supposed to be driven by any suitable motive power applied to any desirable one of said sprocket-wheels.

The endless conveyer-chain I is provided in the usual manner with flights l, which during the lower run of said chain co-operate in the manner shown and well understood with the floor or bottom of the conveyer-trough B.

Immediately over the bottom of the pit C, and running transversely thereof, is located the usual surface track or railway, n, on which travel the car or cars J, which bring the coal to be elevated, and from which the coal is dumped or discharged in the usual and well-known manner into the feed-spout o, which supplies it to the lower portion of the trough B of the chain conveyer.

In the operation of the contrivance or apparatus the coal discharged from the dump or car J directly into the feed-chute o descends by gravity into the lower portion of the trough B of the chain conveyer, from whence it is continuously carried or fed obliquely upward within said trough B, in the usual and well-known manner, by the flights l of the conveyer-chain, the material being discharged, as clearly illustrated at Fig. 1, in the usual manner, into the chute D or any other desired receptacle; but, unlike trough conveyers with endless flighted chains, as heretofore employed in connection with such feed-spouts and cars as I have shown, the conveyer apparatus in my case has the endless chain arranged, as shown, to make a complete circuit round about the car and feed-spout o, so that, as clearly illustrated, there is never any interference of the coal being handled with the upper run of the flighted chain. Furthermore, by reason of having only the lower run

of the chain and the trough of the conveyer located beneath the car and within the pit C, this pit may be made much more shallow 60 than it was heretofore possible to make it with a given degree of inclination to the conveyer-trough B and a given height of elevation of the upper discharge end of said trough, all of which is of great advantage, both with 65 reference to economy in originally constructing the apparatus and as to durability, economy of power in running the chain conveyer, and non-liability of derangement of the conveyer by clogging of any portion of the upper 70 run of its chain with particles of coal.

Of course the precise arrangement of the circuitous endless chain passing around or encompassing the car and the surface track and the exact proportions of the parts shown 75 are not material to my invention, the pith or gist of which lies in such a combination or arrangement of the endless flighted chain of the trough chain conveyer with the supply-car and the track on which it is to be supported as brings only the lower run of the endless chain and the trough of the conveyer beneath the car, while the upper run of the chain passes round about and over the car and the surface railroad.

What I therefore claim as new, and desire to secure by Letters Patent, is—

In an apparatus or contrivance for translating coal from the dumping-cars of a surface railroad to a higher elevation, the combination, with the usual pit located beneath the surface track and adapted to accommodate the lowermost portion of the chain-conveyer trough and to receive the coal as discharged from the dumping-cars located on 95 said track, of, first, the obliquely-arranged conveyer-trough having its lowermost end located within said pit and its upper end at a higher elevation, and, second, the flighted endless conveyer-chain having its lower run arranged to operate in conjunction with said trough, and having its upper run arranged to encompass the track and the dumping-car which may be located thereon, the whole constructed and operating in substantially the 100 manner hereinbefore described, for the purposes set forth.

In witness whereof I have hereunto set my hand this 13th day of July, 1888.

JAMES M. DODGE.

In presence of—

E. R. LOWEREEN,
JOHN DUNN.
